SERVICE GLASS

Abraham Cooperstein, Brooklyn, N. Y.

Application July 31, 1934, Serial No. 737,744

2 Claims. (Cl. 65—13)

The present invention relates to tableware, and particularly to receptacles which are employed for serving sherbet, wine, etc., the lower portion of the receptacle comprising a thin metallic stand, 5 and the upper portion a glass bowl which is adapted to be mounted upon the stand in a removable manner.

Heretofore, the metal stand has taken several forms, the usual form being that of a receptacle 10 comprised of two hollow cones reversely arranged and fastened together by soldering to constitute an upwardly extending cup-like part to receive the glass bowl, and a downwardly extending flared base portion. The upper cone has hitherto been 15 provided at its lower part with an integrally formed screw threaded cylinder having openings at both ends, whereby when the cone-shaped parts of the stand are attached with their reduced ends fastened together, there is a hollow screw 20 threaded opening for receiving the screw threaded stem projecting from the glass bowl. This stem is moulded upon the glass bowl during its process of manufacture, and screws into the threaded cylinder, projecting slightly beyond the 25 lowermost opening.

It has been found that in the use of two-part receptacles such as hereinabove described, the fingers of the user are frequently cut either on the bottom opening of the thin metallic screw threaded cylinder, or else on the sharp edges of the 30 lowermost portion of the glass stem projecting through the cylinder.

One of the objects of the present invention is to overcome this difficulty, and this is accomplished by providing a two-part receptacle which 35 has the cylindrical threaded part completely enclosed at its lowermost end so as to form a smooth and continuous surface.

A feature of the invention constitutes the thimble-like threaded cylinder which comprises a separate part of the receptacle and which is individually fastened in permanent manner in the process of manufacture to the downwardly extending cone base portion. The upper cone is 40 subsequently fastened to the reduced end of the lower cone and the open upper end of the thimble-like cylinder.

In the accompanying drawing wherein like reference numerals indicate like parts throughout 45 the different figures, Fig. 1 illustrates an exploded view of the individual parts of the receptacle of the invention in their proper order of assembling.

Fig. 2 is a rear perspective view of the thimble-like threaded cylinder, forming part of the receptacle, and

Fig. 3 shows a vertical cross-sectional view of the complete receptacle with all the parts in position.

Referring to the drawing in more detail, there is shown a glass bowl which has a flared upper part 1 to which is moulded in the process of manufacture a downwardly projecting screw threaded stem 2. In assembling the complete receptacle, this stem is adapted to fit and screw into the open end 8 of a screw threaded metallic thimble 3 in the form of a cylinder whose lower end 4 is completely enclosed to present a smooth and continuous surface.

The stand comprises the lower substantially cone shaped part 5, the threaded cylinder 3 which is permanently fastened to the upper part 6 of the cone 5, and the upper expanded cone shaped member 7 which is also fastened to the lower cone at 6. The three parts 5, 3 and 7 are formed of relatively thin gauge metal and are preferably secured together and to each other by soldering.

The opening 8 of thimble 3 enables the stem 2 of the glass bowl to be screwed into the threaded portion of the cylinder so that the glass bowl is held firmly in place in the cup shaped upper member 7 whose concavity conforms in outline with the convexity of the glass bowl portion.

It will be noted from an inspection of the drawing that the enclosed end 4 of the thimble 3 is not so wide as the upper end and there is a space between the bottom of stem 2 and end 4 of the cylinder.

What is claimed is:

1. A two-part dish comprising a stand of thin gauge metal formed of upper and lower cone shaped hollow parts, which are fastened together at their small ends, and a threaded thimble having an open end and a closed end, said open end being secured to the juncture of said upper and lower cone shaped parts, said closed end projecting into the flared portion of said lower cone shaped part, in combination with a glass bowl having a convex lower surface fitting into the upper cone shaped part and an integral threaded stem screwed into the threaded thimble.

2. A two-part dish comprising a stand of thin gauge metal formed of upper and lower cone shaped hollow parts, which are soldered together at their contracted ends, and a threaded thimble-like cylinder having an open end and a closed end formed to present a smooth and continuous surface, said open end being soldered to the contracted end of said lower cone shaped part, and said closed end projecting into the flared portion of said lower cone shaped part, in combination with a glass bowl having a convex lower surface fitting into the upper cone shaped part and an integral threaded stem screwed into the threaded cylinder.

ABRAHAM COOPERSTEIN.
